BRACKET FOR TOILET TISSUE HOLDERS

Paul F. Simpson, Washington, Conn., assignor to
The Autoyre Company, Oakville, Conn., a corporation of Connecticut

Application April 28, 1953, Serial No. 24,742

Term of patent 14 years

(Cl. D4—3)

To all whom it may concern:

Be it known that I, Paul F. Simpson, a citizen of the United States, residing in Washington, county of Litchfield, and State of Connecticut, have invented a new, original, and ornamental Design for a Bracket for Toilet Tissue Holders, of which the following is a specification, reference being had to the accompanying drawing, forming a part thereof.

In the drawing,

Fig. 1 is a perspective view of the bracket, showing my new design, the said view showing the bracket associated with toilet tissue holder arms illustrated in dotted lines;

Fig. 2 is a top view of the bracket of Fig. 1 and Fig. 3 is a plan view of the bracket of Fig. 1.

The dominant features of my new design have been illustrated in the drawing in full lines.

I claim:

The ornamental design for a bracket for toilet tissue holders, substantially as shown and described.

PAUL F. SIMPSON.
